FLUID COOLING APPARATUS AND METHOD

George M. Kleucker, St. Louis, Mo., assignor to
 Midwest Coolers, Inc., St. Louis, Mo., a corpora-
 tion of Missouri

Application March 24, 1939, Serial No. 263,864

3 Claims. (Cl. 62—126)

This invention relates to certain new and useful improvements in fluid cooling apparatus and methods.

My invention has for a primary object the provision of fluid cooling apparatus which is economical in construction, operation, and maintenance, and capable of extremely high surface and refrigerating efficiency hitherto thought unobtainable.

My invention also has for an object the provision of a method of refrigeration and cooling which makes possible not only the achievement of heat exchange efficiencies far in excess of anything hitherto thought obtainable, but also extreme simplification of structure and other installed equipment with resultant economies in original investment as well as operation and maintenance, and which is effective and sanitary in the refrigeration and cooling of fluids generally.

And with the above and other objects in view, my invention resides in the novel features of form, construction, arrangement, and combination of parts presently described and pointed out in the claims.

In the accompanying drawings (2 sheets),—

Figure 1 is a vertical sectional view of a fluid cooling apparatus constructed in accordance with and embodying my present invention;

Figure 2 is a transverse sectional view of the apparatus, taken approximately along the line 2—2, Figure 1;

Figure 3 is an enlarged fragmentary sectional view of the apparatus;

Figure 4 is a detail sectional view of the apparatus, taken approximately along the line 4—4, Figure 3;

Figure 5 is a vertical sectional view of a modified fluid cooling apparatus of my invention particularly adapted for use as a liquid cooler;

Figures 6 and 7 are transverse sectional views of the modified apparatus, taken approximately along the lines 6—6 and 7—7, respectively, Figure 5;

Figure 8 is an enlarged fragmentary sectional view of the modified cooler, illustrating in detail the refrigerant distributing means; and

Figure 9 is a detail sectional view of the apparatus, taken approximately along the line 9—9, Figure 8.

Referring now in more detail and by reference characters to the drawings, which illustrate practical embodiments of my invention, the heat exchanger A includes an open-ended cylindrical shell 1 provided at its upper and lower ends with

circular tube sheets 2, 3, which latter project annularly outwardly beyond the periphery of the shell in the provision of attachment flanges 4, 5.

Welded or otherwise fixed upon, and extending respectively upwardly and downwardly from, the flanges 4, 5, are cylindrical walls 6, 7, provided with removable end closure disks 8, 9, in the formation of upper and lower liquid-receiving chambers 10, 11.

10 Mounted in the wall 6 and opening into the chamber 10 above the tube end-sheet 2, is an intake pipe 12, and similarly mounted in the lower wall 7 and opening into the chamber 11 just above the end closure disk 9, is an outlet pipe 13, all as best seen in Figure 1 and for purposes presently more fully appearing.

Welded or otherwise fixed in, and extending transversely across, the shell 1, is an intermediate tube sheet 14 spaced a relatively short distance from the under face of the tube end-sheet 2 in the provision of a liquid refrigerant header space 15.

Mounted in the shell 1 and opening into the header space 15, is a refrigerant inlet pipe 16, and similarly mounted upon, and opening into, the shell 1 just above the upper face of the lower tube end sheet 3, is a refrigerant recirculation pipe 17 connected to a receiving sump tank 18. Near the bottom of the sump tank 18, is a suction connection 19 to a conventional recirculation pump 20, which is at its discharge side connected, in turn, to the refrigerant intake pipe 16.

Also mounted in, and opening to the interior of, the shell 1 below the intermediate tube sheet 14, is a suction line 21 operatively connected to the "low-side" of a conventional refrigerating system (not shown). It will, of course, be evident that a conventional venturi-type recirculating means may be substituted for the pump 20.

40 Mounted in the shell 1 and extending through the walls 2, 3, and 14, is a plurality of longitudinal heat exchange tubes 22 each opening at its upper end into the chamber 10 at its lower end into the chamber 11, all as best seen in Figures 45 1 and 2.

Annularly about each of the tubes 22, the intermediate tube sheet 14 is formed with a series of apertures 23 opening above a frusto-conical distributor ring 24 having an outer laterally extending flange 25 welded or otherwise fixed to the under face of the intermediate tube sheet 14. Each ring 24 has a tube accommodating aperture 26 of slightly greater diameter than the diameter of the particular tube 22 with 55 which it is associated, thereby providing there-

about a narrow annular gap 29, all as best seen in Figure 3 and for purposes presently more fully appearing.

In use, the liquid refrigerant is flooded by recirculating means or pump 20 into the header space 15 and cascades downwardly through the apertures 23, being directed by the respective distributor rings 24 through the annular gap or space 29 in the formation of a rapidly moving continuous film over the outer surface of each of the tubes 22. It will be understood that, due to the velocity and mass of the liquid refrigerant flowing as a rapidly moving sheet, gas bubbles are sheared off at inception and discharged through this liquid refrigerant sheet into the free gas space of relatively large volume. Evaporation from the outer surface of the film thus produces a highly efficient cooling effect. The excess refrigerant collects above the lower tube sheet 3 and is drawn out through the pipe 17 and recirculated by the recirculation pump 20 to the refrigerant intake pipe 16. The evaporated gas is accordingly withdrawn through the pipe 21, to the suction of the compressor (not shown) and the liquid refrigerant having evaporated is compensated for by liquid refrigerant flowing into a separate sump tank 18, which is provided with a conventional liquid level control (not shown). Near the bottom of the sump tank 18 is a suction connection 19 to a conventional recirculating pump 20 which discharges through the pipe 16 into the liquid header 15. The sump or surge tank is conventionally connected by a line 21' to the suction line 21 and the liquid level control therein (not shown) is connected by a line 18' to the condenser (not shown) for supplying liquid refrigerant to the tank 18.

Meanwhile the liquid to be cooled is pumped through the inlet pipe 12 into the liquid-receiving chamber 10 and passes downwardly through the tubes 22 into the lower liquid-receiving chamber 11 and thence outwardly through the outlet pipe 13.

The design of this apparatus lends itself particularly well to the aeration or oxidation of certain liquids, such as wort or milk and to the charging of water with carbon-dioxide. In such instances, the end closure disks 8, 9, of the upper and lower chambers 10, 11, may be made pressure-tight and the collars 6, 7, provided with gas conduits *a*, *b*, shown as optional equipment in dotted lines in Figure 1. Air or gas may be induced to the bottom chamber 11 through the conduit *a*, whence it will pass upwardly through the tubes 22 into the receiving chamber 10 to perform the function of oxidation or carbonization, as the case may be. Excess gas or air is drawn off from the chamber 10 through the conduit *b*.

The modified heat exchanger B of Figures 5 to 9 is more particularly adapted for the cooling of liquids, such as beer, milk, and other beverages, for instance, and comprises an open-ended cylindrical shell 30 provided at its lower and upper peripheral margins with radially outwardly presented annular attachment flanges 31, 32. Extending across the upper and lower ends of, and welded or otherwise fixed to, the shell 30, are upper and lower partition members or tube end-sheets 33, 34. Also fixed in, and extending transverse across, the shell 30 and spaced a short distance from the end-partition 31, is an intermediate partition or tube sheet 35.

Mounted in the shell 30 and extending through the partitions 33, 34, 35, is a plurality of longi-

tudinal cooler tubes 36 each terminating at its respective ends flush with the outwardly presented faces of the upper and lower end partitions 33, 34, all as best seen in Figure 5 and for purposes presently more fully appearing.

The tubes 36 are preferably arranged in a plurality of concentric or multi-pass series 37, 38, 39, and a central more or less axial group 40, each series preferably containing the same number of tubes, all as best seen in Figures 8 and 9 and for purposes presently more fully appearing. It will, of course, be understood in this connection that the tubes 36 may also be grouped in any other multi-pass series or arrangement.

For accommodating the tubes 36, the intermediate partition 35 is provided with a plurality of apertures 43 each opening above a respective frusto-conical ring 44 welded or otherwise fixed upon the under face of the partition 35 and tapering downwardly to a diameter slightly larger than the outside diameter of the accommodated tube 36 in the provision of a narrow annular gap 45, all as best seen in Figures 8 and 9 and for purposes presently more fully appearing.

Removably mounted over the opposite ends of the shell 30, are end domes 46, 47, constructed preferably of sheet metal or other suitable material and peripherally provided with radially outwardly flaring attachment flanges 48, 49, for registering engagement with the shell flanges 31, 32, respectively, as best seen in Figure 5 and for purposes presently more fully appearing.

Removably mounted in the space between the upper tube sheet 33 and the dome 46, is a concentrically disposed cylindrical baffle ring 50 positioned between the cooler pipe series 38 and the cooler pipe series 39 in the provision of concentric distribution chambers 51, 52, all as best seen in Figures 5 and 6. In the event that the tubes 36 are grouped in some other type of multi-pass series or arrangement, as above pointed out, then some other type of more or less conventional baffle means may be accordingly employed.

Similarly mounted in the space between the lower tube end-sheet 34 and the lower dome 47, are two concentrically disposed cylindrical baffle rings 53, 54, the ring 53 being positioned between the cooler tube series 37 and the cooler tube series 38, and the ring 54 being positioned between the cooler tube series 39 and the central or axial group cooler tubes 40 in the provision of concentric distribution chambers 55, 56, 57, as best seen in Figures 5 and 7 and for purposes presently more fully appearing.

The lower dome 47 is further provided with an intake pipe 58 communicating with the distribution chamber 55 and an outlet pipe 59 communicating with the distribution chamber 57.

The shell 30 is also provided with a refrigerant supply line 60 opening into the space between the upper end-sheet 33 and the intermediate partition 35, and is further provided adjacent the lower tube sheet 34 with a refrigerant recirculation line 61, which projects inwardly of the shell 30. Also mounted on and opening into the shell 30 preferably beneath the intermediate partition 35, is a suction line 62 operatively connected to the "low-side" of a conventional compressor system (not shown), all as best seen in Figure 5.

In use, liquid refrigerant is flooded into the header space between the upper partition 33 and the intermediate partition 35 and cascades downwardly through the apertures 43 in the intermediate partition 35 and is directed by the rings 44 or other distributing means through the an-

nular gap 45 in the formation of a rapidly moving continuous cylindrical sheet or film over the outer surface of the cooler tubes 36 and, by evaporation through the outer surface of the film, produces a highly efficient cooling effect. Meanwhile, a liquid, such as milk or beer, is pumped into the distribution chamber 55 through the intake pipe 58 and passes upwardly through the cooling tubes 37 into the distribution compartment 51 and thence flows downwardly through the cooling tube series 38 into the chamber 56. From the chamber 56, the liquid flows upwardly again through the cooler tube series 39 into the distribution chamber 52 and thence downwardly through the cooler tube series 40 and 41 into the distribution chamber 51 and out through the outlet pipe 59. Whenever it is desired, the upper and lower domes 46, 47, and the associated baffle rings 50, 53, 54, may be quickly and simply removed, providing very convenient access to the cooler tubes 36 for cleaning purposes.

Thus it will be seen that, by my invention, I have provided heat exchange methods and means which make possible the achievement of exceptionally high efficiency. In fact, actual experiments have demonstrated that heat exchangers and coolers constructed in accordance with my present invention achieve heat exchange efficiencies or, in other words, K factors which exceed by several hundred percent the efficiencies hitherto obtainable in previously available equipment. As has been pointed out above, this high efficiency is achieved largely by reason of the movement and uninterrupted continuity of the film of liquid refrigerant on the one surface of the medium through which the heat exchange takes place. In addition, the heat exchangers of my present invention, are capable of considerably increased volumetric capacity, as well as greater efficiency.

It will also be evident that the heat exchangers of my present invention are not only extremely efficient in thermal operation, but are also exceptionally sanitary and will meet the most rigid sanitary requirements imposed for the handling of liquids for human consumption.

It should be understood that changes and modifications in the form, construction, arrangement, and combination of parts of the cooling apparatus may be made and substituted for those herein shown and described without departing from the nature and principle of my invention.

Having thus described my invention, what I claim and desire to secure by Letters Patent is,—

1. A cooler including an elongated evaporator shell having a pair of spaced parallel tube sheets mounted therein for dividing the shell into an intake compartment, a discharge compartment, and an intermediate evaporative compartment, a plurality of tubes mounted at their ends in and extending longitudinally between the tube sheets for communication with the intake and discharge

compartments, and an intermediate transverse partition extending transversely across the evaporative compartment and snugly embracing the respective tubes, said partition being provided with a plurality of frusto-conical rings each disposed concentrically around, and spaced throughout from, a respective tube, said partition further having an annular series of spaced apertures around each of said tubes opening into the space between the respective ring and tube for distributing refrigerant around the outer surface of the respective tube in a continuous and uninterrupted film.

2. A cooler including an elongated evaporator shell having a pair of spaced parallel tube sheets mounted therein for dividing the shell into an intake compartment, a discharge compartment, and an intermediate evaporative compartment, a plurality of tubes mounted at their ends in and extending longitudinally between the tube sheets for communication with the intake and discharge compartments, and an intermediate transverse partition extending transversely across the evaporative compartment and snugly embracing the tubes, said partition being provided with a plurality of frusto-conical rings each disposed concentrically about, and spaced throughout from, a respective tube, said partition further having an annular series of spaced apertures disposed around each of said tubes with their longitudinal axes parallel with the longitudinal axis thereof, said apertures opening into the spaces above the oblique surfaces of the respective rings for creating a plurality of downwardly directed jets which are deflected at relatively high velocity by the ring against the associated tube for creating therearound a continuous cylindrical film which moves downwardly covering substantially the entire tube surface with a body of refrigerant having substantial mass and velocity over substantially the entire tube-length.

3. In a vertical sheet-and-tube cooler including a refrigerant header having a horizontal tube sheet and a plurality of vertical heat exchanger tubes extending therethrough, a refrigerant distributing ring fixed upon the under side of the tube sheet in external concentric relation to each tube, said rings each being at its upper end of substantially larger diametral size than the tube and tapering downwardly and inwardly and being at its lower margin spaced from the outer surface of the associated tube in the provision of a restricted annular discharge space, said tube sheet further being provided with a plurality of jet-forming apertures around each of said tubes opening into the space enclosed by the ring for forming a tube encasing film of refrigerant having substantial mass and permitting a slight amount of intermediate expansion of the refrigerant for impelling the refrigerant film downwardly through the annular discharge space with substantial velocity.

GEORGE M. KLEUCKER.
